SERVICE STAND

John J. Sullivan, Norfolk, Va.

Application March 4, 1954, Serial No. 29,314

Term of patent 14 years

(Cl. D13—1)

To all whom it may concern:

Be it known that I, John J. Sullivan, a citizen of the United States, residing at Norfolk, county of Norfolk, and State of Virginia, have invented a new, original, and ornamental Design for a Service Stand, of which the following is a specification, reference being had to the accompanying drawing, forming part thereof.

Fig. 1 is a perspective view of a service stand showing my new design.

Fig. 2 is an elevational view of the opposite side of Fig. 1.

The dominant features of my design reside in the portions shown in full lines.

I claim:

The ornamental design for a service stand, as shown and described.
